Primary Examiner — Melanie Pellegrini(74) *Attorney, Agent, or Firm* — Law Office of Jeff Williams PLLC; J. Oliver Williams(57) **CLAIM**

The ornamental design for a ring apparatus, as shown and described.

DESCRIPTION

FIG. 1 is a front perspective view of a ring apparatus according to the present application.

FIG. 2 is a front view of the ring apparatus of FIG. 1.

FIG. 3 is a rear view of the ring apparatus of FIG. 1.

FIG. 4 is a right view of the ring apparatus of FIG. 1.

FIG. 5 is a left view of the ring apparatus of FIG. 1.

FIG. 6 is a top view of the ring apparatus of FIG. 1.

FIG. 7 is a bottom view of the ring apparatus of FIG. 1; and,

FIG. 8 is an alternate front perspective view of the ring apparatus of FIG. 1.

The broken lines are included for the purpose of illustrating environmental structure and form no part of the claimed design.
